Cyrus A. CLARK
BY Victor J. Evans

ATTORNEY

Patented Sept. 25, 1928.

UNITED STATES PATENT OFFICE.

CYRUS A. CLARK, OF CLAREMONT, CALIFORNIA.

RAZOR-BLADE HOLDER.

Application filed August 25, 1926. Serial No. 131,472.

This invention relates to improvements in handle or holder means for tools and has particular reference to a holder for safety razor blades that can be readily used for a ripping or scraping action.

The principal object of the invention is to provide an economically and simply constructed device of the character described wherein the handle portion of the same can be utilized not only for the purpose of comfortably and conveniently holding the device during the ripping or scraping operation, but also serving as a sheath for the blade.

Other objects and advantages will be apparent during the course of the following description.

In the accompanying drawings forming a part of this specification, and in which like numerals are employed to designate like parts throughout the same,

Figure 1 is a side elevation of the device constructed in accordance with my invention and showing the blade in an inoperative position,

Figure 2 is a similar view showing the blade in an operative position,

Figure 3 is a transverse vertical section through the device on the line 3—3 of Figure 1 and

Figure 4 is a longitudinal section on the line 4—4 of Figure 3.

After a razor blade has been utilized for a shaving operation, the same is ordinarily discarded. While the cutting edge will not suffice for its primary object, namely the shaving operation, nevertheless, there is present sufficient cutting edge that can be utilized for many domestic uses. However, in the use of a razor blade, some means for retaining the same in the hand must be provided and where there is no such means, injury or a cutting of the fingers of the user will result.

I have therefore devised a simply constructed razor blade holder which will securely retain the blade therein and will eliminate the danger of an accident during any desired use of the blade.

In the accompanying drawings wherein for the purpose of illustration is shown a preferred embodiment of my invention the numeral 5 designates a razor blade of the Gem type provided with the usual folded top 6 and cutting edge 7, which blade is rigidly gripped within a tubular handle member 8 preferably formed of stamped sheet metal

which can be easily bent or folded to the desired shape, the inherent elasticity of the metal serving to grip the blade and the top, to prevent displacement of the same.

As shown to advantage in Figures 3 and 4, the numeral 9 designates a metal blank of sheet metal having its body portion of substantially rectangular conformation and having integrally formed therewith a longitudinal extension 10.

It is to be noted that the upper extremity of the body portion and likewise the extension are folded or bent to provide a tubular portion of a larger diameter than the 70 diameter of the tubular member and in which the referred to member 8 is slidably mounted.

The lower extremity of the body portion of the blank is folded upon itself so as to provide a flap 12 which serves as a guard for 75 the exposed edge of the blade.

In order that displacement of the blade holding member from the handle portion may be eliminated I propose to secure to the tubular extension of the body member a thin 80 metal strip 13 which is folded at its extremities to provide inturned ends 14 and 15 which are secured within the tubular member.

The strip so employed limits the longitudinal movement of the handle portion with 85 relation to the blade holding portion and is best illustrated in Figure 2.

In assembling the device the blade is first inserted in the tubular member 8 which in turn is positioned within the tubular portion 90 of the guard member portion of the device. The metal strip 13 is then secured at its ends to the tubular member and the device thus assembled.

In the operation of the device when it is 95 desired to expose the blade for use, it is only necessary to actuate the tubular member 8 so that the same will slide within the tubular portion of the guard and the blade can then be conveniently exposed for use as illustrated 100 to advantage in Figure 2.

From the foregoing description taken in connection with the accompanying drawing it will be evident that I have devised an efficient holder for a razor blade which can be 105 readily used for many domestic purposes such as ripping or cutting cloth, for any desired scraping action or in fact for any light household work requiring a keen cutting edge.

It is to be understood that the form of my 110 invention herewith shown and described is to be taken as a preferred example of the same

and that various changes relative to the shape, size, material and arrangement of parts may be resorted to without departing from the spirit of the invention or the scope 5 of the subjoined claim.

Having thus described my invention, I claim:—

A device of the character described comprising a metal blank bent adjacent its upper extremity to define a tubular top portion 10 and having a flap on its lower extremity, a

tubular razor blade carrying member slidably positioned in the tubular portion of said blank and means carried by said blade carrying member for limiting its lateral movement relative to said blank, said means comprising a metal strip in parallelism with said tubular member and having its extremities connected thereto. 15

In testimony whereof I affix my signature.

CYRUS A. CLARK
